TELEVISION SYNCHRONIZING AND MONITORING SYSTEM

Filed Jan. 5, 1932

The other manner of scanning is by positioning images such as those on a film or plate intermediate the screen 5 and the photoelectric cell 20 thus permitting the varying emergent light 5 to effect the photoelectric cell.

The output of the cell 20 is fed into an amplifier 21 which in turn feeds a modulator 22 for modulating a carrier frequency generated by an oscillator 23. The output of the modulator is amplified in amplifier 25 and is then impressed upon an antenna system 26 for broadcast transmission. Of course transmission may be accomplished over wires in the well known manner.

Referring again to the arc screen, a second field turn 30 represents a second field coil smaller than the coil 9 and which is connected to the output of a synchronizer 31. This synchronizer has two inputs one of which is from an amplifier 32 which is connected to probes 34 and to one 15 of the electrode rails 7. In this input circuit is an adjustable resistance 35 for the purpose of controlling the amplitude of the input to amplifier 32. The other input to synchronizer 31 is from an oscillator 37 through an adjustable resistance 38 and a rectifier 39, oscillator 37 being adjustable as to frequency by means 20 of a variable tuning element 40. The output of the oscillator is also impressed upon the amplifier 21 for modulation of the oscillator 23, and subsequently for transmission simultaneously 25 with the photocell currents, the frequency of this oscillator, however, being low with respect to the frequency of the photocell currents.

The operation of this synchronizing system is 30 similar to that of the synchronizer shown in the above mentioned patent, but will be briefly stated here.

As the arc turns the corners at the right hand side of the screen, it being understood that the probes 34 may also be positioned in the left hand corners, a voltage is induced in the input circuit to the amplifier 32 which voltage is of a pulsating uni-directional nature. After amplification these impulses are impressed upon the 40 input of a vacuum tube within the synchronizer. Simultaneously with the impression of these impulses, other impulses from the oscillator 37 are impressed upon another tube of the synchronizer 31 which neutralizes the impulses from the screen 45 when the arc reaches the corners at the proper instants. The output circuit of the synchronizer has a definite normal current flowing therein. To produce perfect neutralization the frequency of the oscillator 37 is adjusted in conjunction 50 with the arc speed by rheostats 11 and 14. At the proper arc speed, the impulses from the oscillator 37, which are rectified so that only a half cycle of each impulse is impressed on the synchronizer, perfectly neutralize those from the 55 screen. However, should the arc be retarded or advanced in its travel between corners, a differential current will be produced in the output of the synchronizer which will decrease or increase the current already in the winding 30, thereby weakening or strengthening the field and producing the appropriate change in the speed 60 of the arc. This synchronizing system will maintain a constant speed between corners or a constant cyclic speed of the arc.

In Fig. 2 showing the receiving system, the incoming signals are picked up by an antenna 50 amplified in a receiving system 51, and impressed upon a receiving screen 55 having electrodes 56 and 57, similar to those at the transmitter. 70

Connections to the receiver screen 55 include

conductors 59, adjustable resistance 60 and a large capacity element 61. An arc on the screen 55 is created by a direct current source 63, the energy being supplied through an adjustable resistance 64 and a choke coil 65. A field coil 67 is supplied with energy from a source 68 under control of a rheostat 69. This part of the system may be identical with that of the transmitter in Fig. 1 or may vary in dimensions as long as the proper proportions are maintained 10 to increase the linear speed of the arc.

The output circuit of the receiver 51 is also connected to a demodulator 71 for obtaining the synchronizing frequency of the oscillator 37, the demodulator being connected to a filter 74 which segregates from the demodulator output this particular frequency. This frequency is impressed through an adjustable resistance 72 and a rectifier 73 on a synchronizer 75, similar to that at the transmitter. The remainder of the 20 synchronizing circuit, namely, an amplifier 76 with an adjustable resistance 77 and the probes 78 in its input circuit together with a synchronizing field winding 79 are the same as those shown in Fig. 1 or may be constructed in proportion to the size of the screens.

This receiving screen operates as follows: the incoming impulses are impressed over the conductors 59 without demodulation, upon the electrodes 56 and 57, thereby varying the intensity 30 of the arc in accordance with the currents from the photoelectric cell 20 at the transmitter. The image may be formed directly on the arc or may be projected upon a fluorescent screen 81 positioned anteriorly of the screen. Although 35 it is preferable to apply the output of the receiver directly upon the screen electrodes without demodulation, with the present invention the incoming signals may be demodulated before impression on the screen. The synchronizer 75 operates in exactly the same manner as synchronizer 31 at the transmitter, the filter 74 substituting for the oscillator 37 in Fig. 1. It is to be understood, of course, that it is necessary to demodulate the oscillator frequency for the purpose of obtaining the proper frequency for the synchronizer 75, which may be accomplished with the demodulator 71.

Returning now to Fig. 1, the remainder of this circuit will be described as it illustrates the invention. This portion of the circuit constitutes a pair of conductors 80 connected to either the final output of the amplifier 25 or the output of some intermediate stage. One of these conductors 80 includes an adjustable resistance 81 and a large capacity element 82. The conductors are connected to the electrodes 6 and 7 of the arc rail screen 5, to impress on the latter the carrier frequency modulations which constitute the output current being transmitted.

By this return arrangement it was found that the transmitting arc not only followed the speed variations of the receiving arc between corners but that the actual image was mirrored on the transmitting arc and could be observed as clearly as when received at the receiver. This mirroring of the image permitted adjustments to be made in the transmitting apparatus and served as a monitor therefor. Before the connection of this return circuit, the image at the receiver had a tendency to shift not only as a whole, but in sections, so that a blurred effect was obtained. However, when the return connection was made so that the proper proportion of the output currents of the photocell were impressed on the 75

receiving screen, the receiver image immediately became stationary and clear. Thus was provided an equalization of the travel of the two arcs and a clearing up of all blurred effects. Furthermore, 5 the receiver image became visible on the transmitter screen and permitted the effect of adjustment to be noted.

Although the intensity of the transmitting arc was evidently varied, there appeared to be no 10 tendency to decrease the efficiency of transmission but the reverse effect, which could only be explained by the presence of regeneration. For instance, when the image being scanned was dark, less current was received by the cell 20 and 15 less energy was thereby applied to the arc, while at light portions of the image, more current was applied to the arc producing a brighter arc. This effect evidently aided scanning and improved transmission.

20 It is to be understood that the principles of this synchronizing circuit have been disclosed in one particular moving arc system, but other uses will occur to those skilled in the art. The scope of the invention is, therefore, defined by 25 the appended claims.

What is claimed is:

1. In a system for transmitting energy characterized by light and shade densities of an object, the combination of a moving light source 30 for exploring said object, a second moving light source at a distant point for reproducing an image of said object, and means at said transmitter for impressing a portion of the energy generated for transmission on said first light 35 source to produce variations therein corresponding to the variations produced in said second source by the transmitted energy.

2. In a television transmitter system, the combination of an electrodynamic arc screen, a field 40 winding supplying a flux for said screen, means for energizing said screen and said field winding, means for transforming light from said arc modified by the light and shade densities of an object into corresponding variations in electrical currents, and means for obtaining a varied 45 propagation of said arc on said screen in accordance with the variations in said electrical currents.

3. In a television system, the combination of 50 an electrodynamic arc screen, a field winding for said screen, means for energizing said screen and said field winding to produce a moving arc, a second electrodynamic arc screen, a field winding and energizing means therefor, a detecting

device for transforming varying light into corresponding currents for impression on said second screen, said currents varying the speed of said second arc, and means for impressing a portion of said currents generated for impression on said second arc on said first arc to cause said first arc to follow the variations in speed of said receiving arc caused by the currents impressed thereon. 5

4. In a system for the transmission of electrical impulses corresponding to light variations 10 defining an object, means for scanning said object including an electrodynamic arc propagated along electrode rails in a magnetic field, means for energizing said rails and said field, means for controlling the cyclic speed of said arc along 15 said electrode rails, and means for varying the speed of said scanning arc in accordance with the unit area variations in the light and shade densities of said object.

5. The method of synchronizing a receiving 20 electro-dynamic arc with a transmitting electrodynamic arc operating simultaneously at two different points, comprising continuously modulating both of said arcs with currents having proportionally the same variations, said variations 25 being produced by scanning with said transmitting electro-dynamic arc.

6. The method of monitoring an electrodynamic arc television transmitting system comprising impressing on said transmitting arc a 30 portion of the transmission currents to form an image of the object to be transmitted at the transmitter.

7. In a television system, a light source, means for exploring an object with light from said 35 source, means for continuously transforming said light after characterization by the light and shade densities of said object into corresponding electrical currents, means for continuously impressing a portion of the output current generated by said transforming means on said light source, and means for substantially simultaneously impressing electrical currents having the same proportional variations therein upon a 40 second light source. 45

8. The method of synchronizing a transmitting light beam and a receiving light beam adapted to be moved simultaneously at different positions, comprising continuously modulating both of said light beams with currents having proportionally the same variations, said variations being produced by scanning with said transmitting light beam. 50
